UNITED STATES PATENT OFFICE.

GEORGE F. NAAB, OF LAKWOOD, OHIO, ASSIGNOR TO THE NORTH AMERICAN MANUFACTURING COMPANY.

RECUPERATOR-TYPE OIL BURNER.

Application filed November 14, 1927. Serial No. 233,158.

This invention relates to liquid fuel burners and more particularly to oil burners of so called recuperator type which are arranged to employ an air supply at a relatively high temperature for purposes of combustion of a low grade fuel oil mixed with air by an atomizing head which comprises a part of the burner.

One of the difficulties encountered in the employment of such a burner is the tendency of the oil to carbonize in that portion of its passage which is necessarily subjected to the high temperature of the air with which the oil is to be mixed.

It is an object of the present invention to provide means as a part of the burner whereby a cooling medium may be added to the oil passing through the burner whereby the oil may be maintained at a temperature low enough to prevent carbonization practically up to the zone of combustion.

Another aspect of the carbonization problem appears when the burner is turned off after a period of use. Under such conditions even though the burner design may be such that carbonization does not take place during the combustion operation, yet after the fuel and hot air supplies are cut off the burner as a whole quickly rises to such a temperature that residual oil in the burner will carbonize so that the burner cannot again be used without a reopening of the oil passage.

It is a further object of the present invention to employ the cooling medium above mentioned for the purpose of cleaning out the fuel passage in the burner after the fuel supply has been cut off whereby the burner is in perfect condition to properly function at any subsequent time.

A still further object of the invention is to accomplish the specific objects described in a manner entirely automatic so far as the operator is concerned.

The exact nature and further objects and advantages of the invention will be apparent from the following description taken in connection with the accompanying drawing which shows a recuperating type of oil burner in which my invention has been incorporated, the drawing being generally a longitudinal section through pertinent parts of the burner.

The principal part of the burner is a hollow body member 1 which is mounted in any suitable way before an opening into the combustion chamber of a furnace, which may be

provided with the usual reverberatory lining and contents. The body is provided with a forward opening 2 arranged to lead to the combustion chamber, a lateral opening 3 adapted for connection with a low pressure hot air supply, and conveniently a rearward opening closed by a removable plate 4. The plate 4 is bored out to receive the stem 5 of an atomizing head 6 which may be of any familiar type, the stem 5 being hollowed to form a passage way 7 through which fuel may be supplied to the head 6 where it will be suitably mixed with air entering the opening 3, the mixture passing out the opening 2 into the combustion chamber.

The stem 5 is provided with a circumferential groove 8 into which projects the end of a screw 9 carried by a hand wheel 10 in threaded relation as at 11 with the plate 4 whereby the longitudinal position of the head 6 with respect to the opening 2 may be adjusted by rotation of the hand wheel 10. The rearward extremity of the stem 5 is taper bored as at 12 and is screw threaded to a T 13. Into the opposite end of the T 13 is screw threaded a nozzle 14, the forward extremity of which extends within the taper bore 12 of the stem 5. The rearward extremity of the nozzle has connection as through the coupling 15 with an oil supply subject to a suitable valve not shown, whereby oil may pass through the coupling 15, the hollow 16 of the nozzle, the hollow 7 of the stem to the atomizing head 6. The connection with the oil supply includes an element 19 of flexibility to allow for the longitudinal adjusting motion of the stem 5 already described and the oil is supplied at a pressure considerably above that of the hot air supply.

The lateral opening of the T 13 has connection as at 17 with a check valve 18 which may be of the ball check or other suitable type allowing flow into the T , but preventing any flow in the opposite direction. The check valve 18 has connection as through a flexible conduit 19 with a supply of cooling medium at relatively low pressure and low temperature such as air or steam supply.

When the burner is functioning to fire a furnace the operation will be as follows: assuming the head 6 properly adjusted by the hand wheel 10. The fuel oil valve being opened oil is forced under a pressure of up to 25 lbs. per square inch through the passage 7 to the head 6 where it is thoroughly

mixed with air at approximately 1000 degrees and under about a 1 lb. pressure, the mixture passing out through the opening 2.

Under the conditions just described, were no other means provided, the oil traveling through the passage 7 at a comparatively slow speed would be carbonized in that portion of the stem 5 surrounded by the high temperature air in the hollow of the body 1.

10 However, according to my invention, under these conditions a certain amount of relatively cold air passes the check valve 18 and enters the lateral portion of the T 13, at a pressure of say 10 lbs. per square inch and accompanies the oil through the passage 7 with sufficient cooling effect to prevent any carbonization.

15 The nozzle 14 cooperates with the bore 12 at this time so that the introduction of the relatively cold air or steam will not affect, except perhaps to increase, the flow of oil. Any back flow toward the cooling medium supply is prevented by the check valve.

20 When the furnace is to be shut down, cutting off the oil supply leaves a certain amount of oil remaining in the passage 7. Where the oil is shut off before the hot air supply obviously this oil would immediately be carbonized; and even if the hot air supply 25 is immediately cut off residual heat in other parts of the burner would soon be conveyed to the stem 5 and result in carbonization of the oil therein. However, where by invention is employed, when the oil supply is cut off the cooling fluid constantly supplied through the check valve continues to flow through the passage 7 and quickly cleans the passage by carrying with it practically all of the residual oil. If any oil still clings to

the walls of the passage this is cooled sufficiently to prevent carbonization.

40 What I claim is:

1. In a liquid fuel burner, a hollow body having openings arranged to pass high temperature air through the hollow thereof, an atomizing head having a stem extending in said hollow, said stem being tubular and having connection with a fuel supply at pressure greater than that of the air passing through said body and being arranged to convey said fuel to said head, and means for cooling said stem to prevent carbonization of fuel therein and comprising means for adding a cooling medium to fuel entering said stem, said cooling medium being at a pressure greater than that of said air and lower than that of said fuel.

2. In a liquid fuel burner, a hollow body having openings arranged to pass high temperature air through the hollow thereof, an atomizing head having a stem extending in said hollow, said stem being tubular and having connection with a fuel supply at pressure greater than that of the air passing through said body and being arranged to convey said fuel to said head, and means for cooling said stem to prevent carbonization of fuel therein and comprising means for adding a cooling medium to fuel entering said stem, said cooling medium being at a pressure greater than that of said air and lower than that of said fuel, and means for preventing back flow of said cooling medium.

30 35 45 50 55 60 65 70 75 In testimony whereof I hereby affix my signature.

GEORGE F. NAAB.
